CLAIM

The ornamental design for front panel for modular processing system, as shown and described.

DESCRIPTION

FIG. 1 is a perspective view, from the front and above, of a front panel for a modular processing system showing our new design.

FIG. 2 is a front view thereof.

FIG. 3 is a top view thereof.

FIG. 4 is a bottom view thereof; and,

FIG. 5 is a right side view thereof, the left side view being a mirror image.

The broken lines shown in FIGS. 1-5 represent environmental subject matter and form no part of the claimed design. The rear view is omitted and forms no part of the claimed design.
